UNITED STATES PATENT OFFICE.

LAMARTINE C. TRENT, OF LOS ANGELES, CALIFORNIA.

CLASSIFIER.

1,041,909.

Specification of Letters Patent.

Patented Oct. 22, 1912.

Application filed December 29, 1910. Serial No. 599,925.

To all whom it may concern:

Be it known that I, LAMARTINE C. TRENT, a citizen of the United States, residing at Los Angeles, in the county of Los Angeles 5 and State of California, have invented certain new and useful Improvements in Classifiers, of which the following is a specification.

The hereinafter described invention relates to an improved machine mainly designed for separating sand or granular material from slimes flowing from a stamp battery or other machinery for crushing and mixing quartz, ores, clay, sand, in fact, the 10 invention is adapted for use generally wherever the separation of coarse and finer products is to be made in a liquid state; the object being to effectively and expeditiously separate the coarse particles from the liquid 15 material carrying the same, the separation or classifying of the material being carried out as a continuous operation, the coarse material being separated and discharged at one portion of the machine while the 20 lighter portions thereof are forced therefrom through an independent outlet.

To comprehend the invention reference should be had to the accompanying sheets of drawings, wherein—

30 Figure 1 is a top plan view of the improved classifier. Fig. 2 is a longitudinal sectional view taken on line $x-x$ Fig. 1 of the drawings, viewed in the direction of the arrows a , said view illustrating the general 35 arrangement of the working parts. Fig. 3 is a part sectional end elevation on line $y-y$, Fig. 1 of the drawings, viewed in the direction of the arrows a' , disclosing the feed sluice, the interior of the conical drum, the 40 receiving blades for directing the separated coarse material toward the discharge outlet, the shelves for raising the material, the rolls 45 for driving the drum, and the trough for receiving the discharge of the finer material.

In the drawings, the numeral 1 is used to designate any suitable form of a supporting base capable of sustaining the other parts of the machine, and on this base is 50 mounted for rotation two alined supporting rollers 2 and 2', the roller 2 constituting the drive roller which is driven by any suitable means, as, for instance, a power belt working over the fast and loose belt pulleys 3 and 3' 55 mounted on the cross-shaft 4 supporting the said roller 2. The face of the roller 2 is

corrugated or fluted and upon the said rollers 2 and 2' rests and is supported for rotation a drum 5, preferably of conical form carrying a tire or wear surface 5' which bears 60 onto the rollers 2 and 2'. From the interior of the said drum extends a hollow shaft 6, which connects with a diaphragm 6' on the interior of the drum, the said diaphragm being parallel to and concentric with the end 65 of the drum 5. This diaphragm is connected to the outer end 7 of the drum or conical vessel 5 by means of the radial ribs, arms or blades 7', which are employed for receiving and guiding the separated coarse material 70 into the discharge hopper 8 which connects with the outlet opening in the end 7 of the drum or conical vessel 5, which hopper deposits the material into the conveyer or suitable receptacle 8' located for receiving 75 the same.

The outer end section of the drum 5 is formed with a step portion 9 which is of larger diameter than the conical portion of the drum, and it is this step portion of the 80 drum which carries the tire or wear surface 5'. The interior of the said step portion forms an enlarged pocket or circumferential groove 9' for the reception of the settled portions of the material to be treated, which 85 gravitates therein from the main body of the drum through the annular passage-way 10 formed by the diaphragm 6'. Within this enlarged diameter or step portion of the drum are secured a plurality of circumferentially arranged longitudinally disposed shelves, buckets, or vanes 10', which act as 90 paddles or collecting surfaces for gathering up the material confined within the annular groove 9' during the rotary motion of the 95 drum 5 and serve to raise or elevate the same.

The projecting end of the hollow shaft 6 works within a bearing 11 supported by a bracket 12 upwardly projected from the supporting base 1, and the shaft as thus mounted serves the purpose of steadyng the rotatable drum on the sustaining rollers 2 and 2' and holding the same in position endwise thereon. On the said bracket 12 is mounted 100 the feed hopper 12' for the material to be treated, which hopper connects with a downwardly inclined forked sluice 13 extended within the rotatable drum 5 for carrying the liquid material into the machine and discharging the same close to the diaphragm 6'. 110

Into the outer end of the hollow shaft 6

is extended a water supply pipe 13' for admitting water therein, which water is discharged from the inner end of the hollow shaft and escapes through an outlet 14 in the diaphragm 6' into the separating chamber 14' of the rotatable drum.

- In the operation of the machine the liquid material for treatment containing the fine and coarse particles of solids flows from the 10 hopper 12' into the forked sluice 13 and is discharged from the same into the main body or settling chamber 15 of the rotatable drum 5 adjacent the diaphragm 6', the drum 5 rotating during such feed of the 15 material. The action of the revolving drum causes the heavier or coarse particles to gradually settle onto the inclined bottom of the chamber 15 and gravitate through the annular passage-way 10 into the enlarged collecting or annular grooved portion 9' of the drum 5, this settling action being accelerated and assisted by the jolting motion imparted to the drum 5 as the same rotates or revolves over the fluted surface of 20 the roller 2 which causes rapid vibrations tending to cause the coarser material to settle more rapidly in the bottom of the enlarged portion of the drum 5. In thus settling the coarse particles enter between the transversely disposed circumferentially arranged 25 blades, shelves or scoops 10 of the rotating drum 5 and are raised or elevated thereby, the vibrations imparted to the rotating drum packing the material onto the blades, shelves or scoops and allowing the liquid 30 portion to pour or run off as the blades reach the top of the interior diameter of the drum. As the loaded blades approach this point the material held thereon is shaken 35 loose and assisted by the vibrations of the machine falls onto the arms or ribs 7', being gradually guided thereby into the spout 8 which discharges onto the conveyer or receptacle 8' and the separation thus accomplished. The constant rolling of the drum 5 keeps or maintains the finer particles or 40 slimes suspended in the liquid, which is gradually discharged through the overflow outlet 16 into the run-way 16'.
- If it is desired to make an exceedingly close classification or separation, water is introduced through the hollow shaft 6 and allowed to flow between the diaphragm 6' and the head end 7 of the machine. This 45 water finds its way by gravity into the smaller diameter of the machine and in doing so creates a current which keeps every particle of the slimes from entering through the passageway 9' into the enlarged diameter of the rotating drum for the coarse particles; and this back flowing water washes any remaining slimes which may cling or 50 adhere to the granular material flowing into the enlarged portion of the drum.
- To prevent the entire load of the end por-

tions of blades 10 falling onto the ribs 7', there are arranged intermediate the outer end portion of adjacent ribs the short ribs 17 forming deflectors which receive a portion of the falling material and discharge the received material onto the inner portion of the longer rib immediately below the same. The vibrations imparted to the rotating drum causes the heaviest material to settle rapidly to the lowest portion of the drum, to pack the heavier material onto the blades 10 so as to permit of the liquid running off or decanting as the blades are carried upwardly, and finally to shake the packed material from off the blades as they approach a vertical position onto the ribs radiating from the center of the diaphragm 6'.

The described machine is capable for use in connection with all classes of work wherein the separation of heavier particles from material is required. It is designed as a classifier for separating sands or granular material from slimes, producing a clean granular product free from slimes and suitable for cyanid mills or concentrating mills. It is adapted to producing clean sands for percolating tanks or for extracting granular material from slimes for regrinding or to remove the slimes from coarse material before concentrating. It is compact, instantaneous in its action and is devoid of wearing parts requiring but small power and no attention. It is also adapted for washing sand for building and manufacturing purposes, cleaning infusorial earth, liquid clay, cleaning the slimes from filter sand and for any purposes where slime or slurry must be separated from sand or granular material.

While the described arrangement of the working parts is desirable and preferred, it is obvious that the invention is not so confined.

Having thus described the invention what is claimed as new and desired to be protected by Letters Patent is—

1. In an apparatus for the described purpose, the same comprising a horizontally disposed rotatable drum provided with a central discharge in its outer end, a vertically disposed diaphragm secured within the drum, a water supply, mechanism for imparting rotation to the drum, means for feeding material to the interior of the drum, and devices arranged therein for raising the separated heavier particles and discharging the same, said means including a conical projection on said diaphragm leading to said central outlet, separated blades on said projection, and auxiliary relatively short blades on the diaphragm interposed between the said first mentioned blades.

2. In an apparatus for the described purpose, the combination with a horizontally disposed rotatable drum provided with a

discharge outlet and an overflow outlet, a vertically disposed disk shaped diaphragm within the drum extending to a point adjacent the periphery of the drum and separated therefrom by a relatively narrow space, a plurality of radial ribs projecting therebetween and connecting the diaphragm to the outer end wall of the drum, circumferentially disposed elevating devices carried by the drum intermediate the said end wall and the diaphragm, the said diaphragm extending below the level of the material as determined by said overflow outlet, means for feeding water with the material into the drum between the diaphragm and the overflow, and mechanism for imparting rotation to the drum.

3. In a classifier for the described purpose, the combination of a rotatable drum having at one end a discharge outlet, a rear end wall for the drum having a substantially central discharge opening, a diaphragm within the drum and extending at its periphery to a point adjacent to but separated from the interior peripheral wall of the drum, separated radial blades projecting from one surface of said diaphragm and connecting with the end wall of the drum, forming guides to deliver directly to said central discharge opening, blades projecting inwardly from the peripheral wall of the drum, and deflectors interposed between the blades of the drum and radial blades on the diaphragm.

35 4. In a classifier for the described purpose, the combination of a rotatable drum having at one end an overflow outlet, an end wall for the opposite end of the drum having a substantially central discharge opening, a diaphragm within the drum and projecting at its periphery to a point adjacent to but separated from the interior peripheral wall of the drum, separated radial blades projecting from one surface of said diaphragm and connecting with the end wall of the drum, forming guides to deliver directly to said central discharge opening, the diaphragm projecting below the level of the material as determined by the overflow and means for delivering water and material to said drum at a point between the diaphragm and overflow.

5. In a classifier for the described purpose, the combination of a rotatable drum having at one end a circumferential enlarged portion constituting a peripheral pocket, an end wall for the drum having a substantially central discharge opening, the opposite end of the drum forming an overflow, a diaphragm within the drum and extending at its periphery to a point adjacent to but separated from the interior peripheral wall of the drum to the side of said circumferential pocket, separated radial blades projecting from one surface of said diaphragm and

connecting with the end wall of the drum forming guides to deliver directly to said central discharge opening, means for feeding material through the open end of the cylinder to a point between the diaphragm 70 and overflow.

6. In a classifier for the described purpose, the combination of a rotatable drum having at one end a circumferential enlarged portion constituting a peripheral pocket, an end 75 wall for the drum having a substantially central discharge opening, a diaphragm within the drum and extending at its periphery to a point adjacent to but separated from the interior peripheral wall of the drum to the side of said circumferential pocket, separated radial blades projecting from one surface of said diaphragm and connecting with the end wall of the drum, forming guides to deliver directly to said 80 central discharge opening, the drum being open at its opposite end to form an overflow, means for feeding material to be treated through the open end of the cylinder to a point adjacent the diaphragm, and means 90 for delivering water to the opposite side of the diaphragm.

7. In a classifier for the described purpose, the combination of a rotatable drum having at one end a circumferential enlarged portion 95 constituting a peripheral pocket, an end wall for the drum having a substantially central discharge opening, a diaphragm within the drum and extending at its periphery to a point adjacent to but separated from the interior peripheral wall of the drum to the side of said circumferential pocket, separated radial blades projecting from one surface of said diaphragm and connecting with the end wall of the drum, forming guides to deliver directly to 100 said central discharge opening, means for delivering water and material to be treated into the drum at a point adjacent one side of the diaphragm, and means for introducing water to the opposite side of the diaphragm.

8. In a classifier for the purpose described, the combination of a horizontally disposed rotatable drum having at one end an overflow outlet and at its opposite end a discharge outlet, a diaphragm positioned in the drum and extending below the level of material established by the overflow outlet, means for feeding material and water into 115 the drum between the diaphragm and overflow outlet, and elevating means carried by the drum to the opposite side of the diaphragm, and guide ribs on the diaphragm to lead the material from the elevating means 120 to the discharge outlet.

9. In a classifier for the described purpose, the combination of a horizontally disposed conical rotatable drum, the smaller end of which being open and constituting an over- 130

flow, and a wall for the opposite enlarged end having a central discharge opening, said enlarged end of the drum forming a pocket, a diaphragm within the drum adjacent the 5 enlarged end and extending below the level of the material established by the overflow outlet, said diaphragm being separated at its edge from the wall of the drum, means for feeding material and water to the drum 10 between the diaphragm and overflow outlet, and means interposed between the dia-

phragm and discharge end wall of the drum for elevating and guiding the material to said discharge.

In testimony whereof I have signed my 15 name to this specification in the presence of two subscribing witnesses.
